UNITED STATES PATENT OFFICE.

WILLIAM C. FISHER, OF MIDDLETOWN, CONNECTICUT, ASSIGNOR TO THE RUSSELL MANUFACTURING COMPANY, OF MIDDLETOWN, CONNECTICUT.

WOVEN CARTRIDGE-BELT.

SPECIFICATION forming part of Letters Patent No. 773,066, dated October 25, 1904.

Application filed June 23, 1903. Serial No. 162,815. (No model.)

To all whom it may concern:

Be it known that I, WILLIAM C. FISHER, a resident of Middletown, in the county of Middlesex and State of Connecticut, have invented certain new and useful Improvements in Woven Cartridge-Belts; and I do hereby declare the following to be a full, clear, and exact description of the invention, such as will enable others skilled in the art to which it applies to make and use the same.

My invention relates to an improvement in cartridge-belts, the object of the invention being to provide a cartridge-belt composed of woven material having a body portion provided with pockets woven thereon and woven-strap portions narrower than the body portion and connected with said body by tapering woven webs.

With this object in view the invention consists in a woven cartridge-belt comprising a wide body portion having pockets woven integral therewith, the ends of the body portion having short tapering woven portions and narrow buckle-straps woven integral with the smaller ends of said tapering portions, said buckle-straps being narrower from their juncture with the tapering portions to their free ends than said body portion.

In the accompanying drawings, Figure 1 is a view in elevation, illustrating my improvements; and Figs. 2 and 3 are views in section.

1 represents the body portion of the belt, 2 the cartridge-pockets, and 3 the narrow buckle-straps.

My improved belt is composed of woven selvaged material, with the pockets 2 having their sides woven thereon in one continuous

weave, and the narrow buckle-straps are connected in weaving with the body portion by tapering woven portions 4, said buckle-straps being of substantially uniform width from their juncture with the tapering portions 4 to their free ends.

While I have shown the buckle-straps about two-thirds the width of the body portion, they may be made narrower, if desired. By uniting the buckle-straps with the body portion through the medium of the integral tapering portion, as above described, no warp or weft threads are left exposed and no metal or other binding for any portion of the edges of the belt is necessary.

Any desired form of buckle may be employed, and I do not restrict myself to any particular construction of connecting device.

Having fully described my invention, what I claim as new, and desire to secure by Letters Patent, is—

An article of manufacture consisting of a woven cartridge-belt comprising a wide central body portion having pockets with their sides woven integral therewith, and narrow buckle-straps connected with the body portion by tapering portions, each edge of the belt throughout its length being formed with a continuous woven selvage edge or binding.

In testimony whereof I have signed this specification in the presence of two subscribing witnesses.

WILLIAM C. FISHER.
